UNITED STATES PATENT OFFICE

FRANK N. MARIANI, OF NEW YORK, N. Y.

DESIGN FOR AN AUTOMOBILE RADIATOR CAP ORNAMENT

Application filed September 21, 1931. Serial No. 41,173. Term of patent 3½ years.

To all whom it may concern:

Be it known that I, FRANK N. MARIANI, a subject of the King of Italy, residing at No. 1 Minetta Street, in the city of New York, county of New York, and State of New York, and whose post-office address is No. 54 Bleecker Street, in the city of New York, county of New York and State of New York, have invented a new, original, and ornamental Design for an Automobile Radiator Cap Ornament, of which the following is a specification, reference being had to the accompanying drawings, forming part thereof, in which

Fig. 1 is a plan view of an automobile radiator cap ornament showing my new design,

Fig. 2 is a side view, and

Fig. 3 is a front view of the same.

I claim:

The ornamental design for an automobile radiator cap ornament, substantially as shown.

FRANK N. MARIANI.
